CLAIM

The ornamental design for a storage box, as shown and described.

DESCRIPTION

FIG. 1 is a front, right and top perspective view of a storage box showing our new design;

FIG. 2 is a front, right and bottom perspective view thereof; FIG. 3 is a front, right and top perspective view thereof, shown in an opened state with the cover and locking features removed, and the storage tray in broken lines;

FIG. 4 is a front, right and top perspective view thereof, shown in an opened state, with the cover, locking features, and storage tray removed;

FIG. 5 is a front view of the storage box of FIG. 1;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is a partial enlarged view of portion 11 shown in FIG. 2;

FIG. 12 is a front, left and top perspective view of the storage box of FIG. 1, shown in a folded state; and,

FIG. 13 is an exploded perspective view of the storage box of FIG. 1.

The broken lines depict portions of the storage box that form no part of the claimed design.
